CLAIM

The ornamental design for a lagging tread for a pulley, as shown and described.

DESCRIPTION

FIG. 1 is a perspective view of a lagging tread for a pulley in accordance with my design;

FIG. 2 is a top plan view of the lagging tread for a pulley;
FIG. 3 is a front view thereof looking generally along the line 3—3 of FIG. 2;

FIG. 4 is a back side view thereof looking generally along the line of 4—4 of FIG. 2;

FIG. 5 is an end view thereof looking generally along the line 5—5 of FIG. 2; and,

FIG. 6 is a bottom plan view thereof.

The broken lines in FIG. 1 represent the environment in which the lagging tread for a pulley is used and forms no part of the claimed design.
